UNITED STATES PATENT OFFICE.

JOHN G. POOL, OF DAYTON, OHIO.

MEANS FOR SUSPENDING FASTENING ELEMENTS FROM CONCRETE.

1,341,585.

Specification of Letters Patent.

Patented May 25, 1920.

Application filed September 26, 1919. Serial No. 326,607.

To all whom it may concern:

Be it known that I, JOHN G. POOL, a citizen of the United States, residing at Dayton, in the county of Montgomery and State 5 of Ohio, have invented certain new and useful Improvements in Means for Suspending Fastening Elements from Concrete, of which the following is a specification.

The principal object of the invention is 10 the provision of a simple, cheaply constructed and efficient device designed to save the drilling of holes in concrete for the purpose of suspending bolts or other fastening elements from the latter. The invention 15 contemplates a device which may be readily attached to a form before the concrete is poured, and into which a bolt may be easily inserted after the form is removed, for the purpose of attaching structures such as radi- 20 ators to ceilings and other concrete surfaces.

Other important and incidental objects will be brought out in the following specification, and particularly set forth in the sub-joined claims.

25 The preferred form of embodiment of my invention is illustrated in the accompanying drawings, of which Figure 1 is a side elevational view, partly in section, of my means for suspending bolts from concrete, attached 30 to a form. Fig. 2 is a top plan view of said means. Fig. 3 is an end view of the latter. Fig. 4 is a side elevational view, partly in section, of the device supporting a bolt after the form has been removed. And Fig. 5 is 35 a plan view of the lid that prevents concrete from entering the bolt receiving portion of the device.

Throughout the specification and drawings, similar reference characters denote cor- 40 responding parts.

Referring to the accompanying drawings, the numeral 1 designates a preferably cradle-shaped member constructed of cast iron, although it may be made of malleable 45 iron or other suitable metal. The sides and ends of the member 1 preferably incline in- wardly to a bottom 2 in which a T slot 3 or other suitable slot is provided to receive a bolt 4. The ends of the member 1 termin- 50 ate in upwardly-projecting curved flange portions 5, 5, which assist in firmly anchor- ing said member in the concrete.

At two diagonally opposite corner edges 55 of the top portions of the member 1, a horizontal outwardly-turned ear 6 is provided.

Each of the ears 6 contains a hole 7 through which a nail 8 is adapted to be passed for a purpose to be hereinafter described. (See Figs. 2 and 3.)

Provided on the top edge of each side of 60 the member 1, and extending therealong from a point near its respective ear 6 to the flange portion 5 farthest from the ear, is a flange 9. The flanges 9, 9, as well as the flanges 5, 5, are narrower than the top por- 65 tions of the side and end members, to permit the latter to support, between said flanges, a lid 10 preferably constructed of sheet steel. At two diagonally opposite corners of this lid, which is rectangular in 70 shape, is a horizontal ear 11 containing a hole 12 that is adapted to register with a hole 7 in the ear 6 upon which the ear 11 rests when said lid is in place upon the member 1. This lid serves the purpose of 75 preventing concrete from entering the bolt receiving space in the member 1 when said concrete is poured.

In operation, the member 1, with the lid 80 10 in place thereon, is secured to a ceiling form 13 by passing nails 8, 8 first through the registering holes 12 and 7 in the ear portions of the lid and member, and then driving those nails firmly into the form as shown in Fig. 1. Concrete 14 is then poured 85 to form the ceiling, in which the member 1 is completely embedded. The form 13 is then removed and the nails 8, 8 filed off at the ceiling line. The lid 10 has prevented any concrete from entering the hollow in- 90 terior of the member 1, which provides a space to receive a bolt head that is inserted therein through the cross portion of the T slot 3 in the bottom 2 of said member. After being so inserted, the head of the bolt is 95 moved above the narrower portion of the T slot, by the edges of which it is firmly sus- pended to permit the attachment of radi- ators or other structures thereto. It is thus unnecessary to drill holes in the concrete 100 to receive the bolts.

While I have shown a removable lid for the member 1, it may be provided with an integral cover without departing from the spirit of the invention. Furthermore, other 105 forms of fastening elements having head portions, other than bolts, may be suspended from my device.

I do not desire to be limited by the de- tails of construction and arrangement herein 110

shown and described, and any changes or modifications may be made therein within the scope of the subjoined claims.

Having described my invention, I claim:

- 5 1. A device for suspending fastening elements from concrete, comprising a hollow cradle-shaped member adapted to be embedded in the concrete, a cover for the top portion of said member to prevent the concrete from reaching its hollow interior, and a pair of diagonally opposite horizontal ears projecting outwardly from the top of said member, each ear containing a hole that receives a fastening element adapted to be passed into a form for the concrete, firmly to hold the cradle-shaped member thereto while the concrete is being poured.
- 10 2. A device for suspending fastening elements from concrete, comprising a hollow cradle-shaped member adapted to be em-

bedded in the concrete, a ledge formed on the top interior portion of said member, a pair of diagonally opposite horizontal ears projecting outwardly from said ledge, with which they are integral, a cover adapted to rest upon said ledge, and a pair of diagonally opposite ears on said cover, adapted to rest upon the ears on said ledge, each pair of superimposed ears containing registering holes that receive a fastening element adapted to be passed into a form for the concrete, firmly to hold the cradle-shaped member thereto while the concrete is being poured and also to hold the cover firmly on the ledge.

In testimony whereof I have hereunto set my hand this 23rd day of September, 1919.

JOHN G. POOL.

Witness:

HOWARD S. SMITH.
